PUTTER HEAD

Joseph A. Delgadillo, Pico Rivera, Calif., assignor of a fractional part interest to Henry Rivas, Hacienda Heights, Calif.

Filed June 29, 1972, Ser. No. 267,371

Term of patent 14 years

Int. Cl. D21—02

U.S. Cl. D34—5 GH

FIG. 1 is a perspective view of a putter head embodying my new design;

FIG. 2 is a rear elevational view thereof;

FIG. 3 is a top plan view thereof;

FIG. 4 is a toe end elevational view thereof;

FIG. 5 is a heel end elevational view thereof; and

FIG. 6 is a bottom plan view thereof.

I claim:

The ornamental design for a putter head, substantially as shown and described.
